UNITED STATES PATENT OFFICE.

THOMAS L. STURTEVANT, OF FRAMINGHAM, AND MILTON G. DAVIS, OF SOMERVILLE, MASSACHUSETTS.

ATTRITION-MILL.

SPECIFICATION forming part of Letters Patent No. 372,436, dated November 1, 1887.

Application filed July 30, 1886. Serial No. 209,510. (No model.)

To all whom it may concern:

Be it known that we, THOMAS L. STURTEVANT and MILTON G. DAVIS, citizens of the United States, residing at Framingham and 5 Somerville, in the county of Middlesex and State of Massachusetts, have invented certain new and useful Improvements in Attrition-Mills; and we do hereby declare the following to be a full, clear, and exact description of the 10 invention, such as will enable others skilled in the art to which it appertains to make and use the same, reference being had to the accompanying drawings, and to letters or figures of reference marked thereon, which form a part of 15 this specification.

This invention relates to attrition mills or screens, more particularly that class in which the screening-surface is composed of a series of similar sections or screen-plates, which form 20 the screen as an entirety, and which are removable for repairs, or replacement when worn out.

Our improvements relate to the peculiar construction and arrangement of certain of the 25 sectional screen-plates, which form a roof or approximately A-shaped screen, as shown in Figure 2 of the drawings, projecting into the interior of the mill, whereby a largely increased screening-surface is obtained, the novel 30 features of which will be hereinafter more fully described and claimed.

Our invention is especially adapted to suit a certain class of attrition-mills, in which two oppositely-rotating heads co-operate with the 35 case of the mill in the reduction or grinding of hard material or mineral-bearing rocks. In mills of this class the interior of the mill-casing is circular in form and usually provided with a screen-holder, partly circular in form, 40 which retains the screening portion formed by plates affixed upon its interior.

In operating these attrition-mills, so rapid is the reduction of the material that every possible means must be adopted in order to expedite the removal of the comminuted material 45 and pass it rapidly away to prevent clogging of the mill, and thereby secure its greatest efficacy.

The drawings represent in Fig. 1 a vertical 50 transverse section of an attrition-mill contain-

ing our screen. Fig. 2 is a longitudinal vertical section of the same on line *xx*, Fig. 1. Fig. 3 represents a perspective view of one of our screen-plates. Fig. 4 is a partly-sectional elevation, enlarged, of a series of screen-plates 55 of the form shown in Fig. 3 in position. Fig. 5 is a perspective view, and Fig. 6 a cross-section, of another form of screen-bar to be substituted for the perforated ones shown in Fig. 2. Fig. 7 is another form of screen-plate 60 slightly modified from that shown in Fig. 3.

In the drawings, A designates the casing of an attrition-mill, which is preferably circular in cross-section and provided with a hopper, B, through which the material fed to the mill 65 is passed. Below the screen is formed a passage, C, which connects with said screen, whereby all the ground material capable of passing through the latter is delivered and conveyed to proper storage-receptacles. Lat- 70 erally of the said casing A are disposed two rotary heads, D D, actuated by suitable shafts and provided with two circular hollow bushings, E E, which project slightly into the mill-casing. When the mill is in operation, one 75 head revolves rapidly in one direction and the other runs with equal velocity in the reverse direction, or both may run in the same direction.

The interior of the mill is provided with a 80 series of screen-plates, *a a*, arranged in circular form and supported upon rings *b b*, which are V-shaped in cross section and secured to the casing A. This screening-surface is constructed of a series of plates which may be 85 varied in form. Thus in Fig. 2 the plates *a a* are perforated with conical holes *c c*, with the apex of the cones directed toward the interior of the mill; but in Figs. 1, 5, and 6 a different form of plate, *a' a'*, is shown, which may be 90 substituted with equally good results. These latter screen-plates are truncated prisms in cross-section, and are curved exteriorly at *d*, Fig. 6, to conform to the contour of rings *b b*, by which they are supported. In lieu of being perforated the plates *a'* are provided with lateral wedge-shaped ribs *e e*, disposed on either side of said plates, and provided alternately with recesses *f f* and lugs *g g*, whereby the adjacent screen-plates are interlocked and 95 100

funnel-shaped. Radially-disposed spaces *h h* are left between said plates forming the screen.

Hitherto the screening - surface has been limited by the shape and diameter of the mill, 5 and, from the rapidity with which the machine acts upon material in process of reduction, much difficulty has been experienced in getting rid of the fine-ground material. To overcome this trouble and at the same time 10 increase the screening-surface without increasing the size or diameter of the mill, we have constructed a series of similarly-shaped polygonal screen-plates, *F F*, preferably approximately **A**-shaped, or in the form of truncated 15 prisms in vertical section. These plates are arranged vertically and parallel with each other, while they project into the interior of the mill beyond the rest of the screening-surface, and rest on the screen-holder formed by 20 the curved rings *b b*. When these screen-plates *F F* are placed in position, they form a roof-shaped screening-surface which projects into and occupies a portion of the interior of the mill, in contradistinction to the other 25 screening portion, which coincides with the interior diameter of the mill. The interstices *j j*, formed between two adjacent plates, being vertically situated, are best disposed to facilitate the discharge of the particles passing 30 therethrough. Each of these polygonal screen-plates has its sides inclined, so as to converge, as shown in Figs. 2 and 3, giving them approximately the shape of the letter **A**, truncated and with no cross-line. By reference to 35 Figs. 3 and 4 the general arrangement and construction of these polygonal screen-plates *F* will be readily understood.

In Fig. 3, which represents a perspective view, we have shown a plate which, to prevent 40 clogging, is composed of a thin triangular shaped piece, *k*, about which, on that portion projecting into the mill, is formed a thickened rim, *l*, which inclines on both sides toward the piece *k*. The perimeter of the plate 45 *F* operates as the active surface of the screen; hence, as the thickness of the individual plates is least in the middle, the spaces *j j*, formed between the adjacent plates, are best adapted to prevent clogging—that is, they are **V**-shaped. 50 in cross-section, with the narrow part thereof next the material to be screened, and thus the ground material readily clears itself.

To interlock and unite the individual plates *F F* as an entirety, three female lugs, *n p s*, are 55 cast upon one side of each plate, while upon the opposite side, and correspondingly located, are three male lugs, *n' p' s'*, whereby, when the plates are in position, their adjacent faces are held apart and thus form the interstices or 60 openings *j j*. The lugs of one plate engage the corresponding lugs upon the next plate, and the plates, as a whole, are rigidly secured together. This may be done by passing bolts

through holes in the upper parts of the screen plates. One such hole is shown in one of the 65 screen-plates *F*, Fig. 3.

Owing to the peculiar action in mills of this class, in which the material in process of pulverization is its own reducing agent, no trouble or interference in the grinding occurs by 70 the inward-protrusion of the screen-plates *F F*, while at the same time the amount of screening-surface obtained is about twice as much as when an ordinary plane or curved surface is employed. 75

It is evident that the polygonal plates may be made of various heights. Thus the distance which they project beyond the normal screening-surface may be changed to suit circumstances or the material to be ground, and in 80 this manner the screening-surface will be increased or diminished, respectively, as the height of the plates *F F* within the mill is increased or diminished. Moreover, the sides of the individual plates *F* may be changed in 85 their obliquity, or, as shown in Fig. 7, they may be vertical. This latter form of plate would be better adapted in the event of employing but one revolving head.

Having thus described our invention, what 90 we claim as new, and desire to secure by Letters Patent, is—

1. The combination, with a curved screen composed of similar plates, *a' a'*, with funnel-shaped screening-orifices therebetween, and 95 the truncated prismatic-shaped plates *F F*, projecting beyond the other screen-surface, of the mill-casing, wherein said screen is secured, and the two rotating grinding-heads, substantially as set forth. 100

2. The projecting polygonal screen-plates *F*, consisting of the lateral oppositely-disposed lugs *n p s*, *n' p' s'*, the central reduced plane portion *k*, and the thick rim *l*, partially surrounding the latter and inclined on both sides to its juncture with said reduced portion *k*, substantially as herein stated. 105

3. A raised roof-shaped screen constructed with the exterior or active screening-surface polygonal to present the largest surface possible, and thereby to increase the screening capacity, substantially as described. 110

4. A raised screen composed of a series of screen-plates, the individual plates being arranged to form clearance-spaces therebetween, which are funnel-shaped in cross-section and vertically disposed, substantially as and for the purpose set forth. 115

In testimony whereof we affix our signatures in presence of two witnesses.

THOMAS L. STURTEVANT.
MILTON G. DAVIS.
